(57) **CLAIM**

The ornamental design for a baffle with anti-reverse stoppers, as shown and described.

DESCRIPTION

FIG. 1 is a front perspective view of the baffle with anti-reverse stoppers;

FIG. 2 is a top plan view of the baffle with anti-reverse stoppers;

FIG. 3 is a bottom plan view of the baffle with anti-reverse stoppers;

FIG. 4 is a right side elevational view of the baffle with anti-reverse stoppers;

FIG. 5 is a left side elevational view of the baffle with anti-reverse stoppers;

FIG. 6 is a front elevational view of the baffle with anti-reverse stoppers;

FIG. 7 is a rear elevational view of the baffle with anti-reverse stoppers;

FIG. 8 is a first cross-section view of the right side of the baffle with anti-reverse stoppers, taken along line 8-8 of FIG. 2; the left side being a mirror image thereof; and,

FIG. 9 is a second cross-section view of the right side of the baffle with anti-reverse stoppers, taken along line 9-9 of FIG. 2; the left side being a mirror image thereof.

The broken lines shown in the drawings are for illustrative purposes only and form no part of the claimed design.
